FOREIGN PATENT DOCUMENTS

CN 306892915 * 10/2021

Primary Examiner — Paula Allen Greene

(57) **CLAIM**

The ornamental design for an ear phone cover, as shown and described.

DESCRIPTION

FIG. 1 is a perspective view of an ear phone cover showing the new design;

FIG. 2 is a rear view thereof;

FIG. 3 is a front view thereof;

FIG. 4 is a side view thereof;

FIG. 5 is an opposite side view thereof;

FIG. 6 is an end view thereof; and,

FIG. 7 is an opposite end view thereof.

1 Claim, 7 Drawing Sheets
